Application March 17, 1933, Serial No. 661,265

23 Claims. (Cl. 93—3)

This invention relates to methods and apparatus for the formation of packages and to correlated inventions and discoveries whereby and therewith the same may be enhanced.

5 In general it is an object of the invention to provide methods and apparatus whereby various of the steps involved in the formation of a lined package may be carried out with effectiveness and efficiency.

10 Another object is the provision of an improved method for forming carton liners and other types of bags.

Another object is the provision of an improved method for the sealing of packages.

15 Another object is the provision of improved apparatus for the formation of carton liners and other bags.

Another object is the provision of improved apparatus for the sealing of packages.

20 A further object is the provision of a method and apparatus for the efficient and effective sealing of liners and other bags formed of waxed paper and the like.

Other objects of the invention will in part be 25 obvious and will in part appear hereinafter.

The invention accordingly comprises the several steps and the relation and order of one or more of such steps with respect to each of the others, and the apparatus embodying features of construction, combinations of elements and arrangement of parts which are adapted to effect such steps, all as exemplified in the following detailed disclosure, and the scope of the application of which will be indicated in the claims.

35 For a fuller understanding of the nature and objects of the invention, reference should be had to the following detailed description taken in connection with the accompanying drawings, in which:

40 Figures 1 and 2 are, respectively, side and plan views of bag-forming apparatus embodying the invention, with certain of the conventional parts omitted, and illustrate one manner in which steps embodying the invention may be performed;

45 Figs. 3 and 4 are, respectively, side and plan views shown as continuations of Figs. 1 and 2, respectively, and illustrate apparatus and a method embodying the invention for closing a lined carton;

50 Fig. 5 is a detail view illustrating a modified form of plunger and a modified form of sealing means;

Fig. 6 illustrates another modified form of such 55 a mechanism;

Fig. 7 is a detail plan view of a modified form of flap-bending-and-pointing mechanism;

Figs. 8 and 9 are plan and transverse sectional views, respectively, illustrating a modified form of mechanism for folding a sealed liner;

5

Fig. 10 is a plan view of another modified form of mechanism for folding a liner and closing the end flaps of a carton;

Fig. 11 is a diagrammatic showing of various of the steps involved in the formation of a package 10 by the use of the apparatus and methods illustrated in Figs. 1 to 10, inclusive;

Fig. 12 is a plan view of a mechanism for closing a side flap carrying a tab;

Figs. 13 and 14 are transverse sectional views, 15 respectively, along the lines 13—13 and 14—14 in Fig. 12;

Fig. 15 is a side view illustrating apparatus and method for pointing and sealing an unenclosed bag;

Figs. 16 and 17 are, respectively plan and side views showing a modified form of mechanism for transferring and conveying packages to be sealed;

20

Fig. 18 is a side view of a modified form of bag-forming mechanism; certain of the conventional parts being omitted, and illustrating a manner in which a modified method may be carried out;

25

Fig. 19 is a sectional view on the line 19—19 of Fig. 18; and

30

Fig. 20 is a view similar to the first part of Fig. 11 showing the steps of constructing a bag by the method and apparatus illustrated in Figs. 18 and 19.

In the formation of bags, lined cartons, etc., it is 35 of importance that a high degree of efficiency of operation be obtained. It is also of importance in the formation of many types of packages that the goods be effectively sealed. One of the main

purposes of such sealing in many cases is to prevent the entrance of moisture to a point within 40 the package where it will affect the goods.

Water-proof sheet material such, for instance, as waxed paper, and paper coated or impregnated with other moisture-proofing materials is used to 45 a large extent in such packaging operations, particularly as liners for cartons. For instance, there

may be used ordinary paper carrying a mineral wax (e. g., paraffin), an animal wax (e. g., beeswax), or a vegetable wax (e. g., carnauba wax),

moisture-proof cellophane having wax associated therewith, papers coated or impregnated with wax-containing nitrocellulose material; resin-coated or resin-impregnated paper, and paper impregnated with latex, etc. The attainment of a

50

moisture-proofing material having wax associated therewith, papers coated or impregnated with wax-containing nitrocellulose material; resin-coated or resin-impregnated paper, and paper im-

pregnated with latex, etc. The attainment of a 55

sufficiently high degree of moisture-proofing in commercial operations effectively to protect the goods is, however, a matter of considerable difficulty and resort is often had to additional and 5 otherwise unnecessary layers of moisture-proofing material on the outside of the carton. Other purposes of such sealing is to render carton liners or other bags sift-proof, grease proof, stain-proof, etc; since it is of importance in many cases that 10 the goods be retained securely in the bag and that the outer surface of the package be not discolored or otherwise adversely affected. For instance, a sift-proof bag is of advantage for holding flour and a sift- and stain-proof liner containing coffee 15 will prevent the discoloration of the carton.

A feature of the present invention resides in the provision of methods and means whereby effectively sealed carton liners and other bags may be readily provided, and the invention permits the 20 provision of desirably sealed bags of many types and for a wide variety of uses. An additional feature of the invention resides in the provision of particularly efficient modes of operation and mechanisms for the formation of bags, lined car- 25 tons and other packages; and various other features will be apparent from the following description.

In accordance with the invention one or more stripes of adhesive may be applied to a web of 30 paper or other material in such positions that when cut and formed into bag shape a stripe of dry adhesive will be provided at the top of the bag, adhesive being applied at other positions desirable for the formation of the bag as de- 35 sired. After filling, the bag is sealed by means of the dry adhesive. In certain of its aspects the invention contemplates pointing the top of the bag and sealing it by a straight line operation which forms creases only at the ends of the bag. 40 If the sheet material and adhesive used are of such nature that they do not seal readily, it is of importance that the dried adhesive extend about all the contacting inner surfaces of the bag, although this is not essential in other cases. As 45 will be apparent, the adhesive may be applied to sheets after cutting or may be applied in whole or in part to a web or sheet at a point remote from the bag-forming mechanism, as at a paper manufacturing plant, if desired, and may in all 50 events be applied in any of a variety of positions and the bag formed in any of a variety of ways, two types of procedure and certain mechanisms therefor which are particularly desirable for use being exemplified. As above indicated, the for- 55 mation of bags from sheets of waxed paper may be readily carried out in accordance with the invention.

In the formation of packages embodying lined cartons the invention contemplates the suitable 60 spreading of the flaps of the carton, the pointing of the liner, the pinching of the liner to seal the same, the bending of the pinched portion laterally, and the closing of the flaps. It is to be understood that in the broader aspects of the in- 65 vention any of a wide variety of sealing means may be utilized and that in the formation of lined cartons in the manner just indicated, a wide variety of mechanisms and steps may be utilized in effecting the operation.

70 In Figs. 1 and 2, there is illustrated a form of procedure and apparatus whereby lined cartons may be efficiently and effectively formed in accordance with the invention.

In the illustrated construction, the moving 75 parts may be driven from suitable power means

such as an electric motor, not shown, and suitably interconnected as by gearing. Various operating parts and interconnecting mechanisms which may be of types well known in the art are omitted in order to avoid prolixity. 5

A pair of rolls 10 and 11 serve to draw a web 12 from a roll 13 over the roller 14 and under glue-applying rolls 15 and 16, whereby a wet adhesive, suitably supplied as from a glue trough 17, is applied to the edges of the web to form stripes 18 and 19. Beyond the rolls 15 and 16 and underneath the web, there is provided a suitably-formed member which may be a plate 20 heated throughout or at its ends to dry the wet adhesive. Conveyor belts 21 are driven from the roller 11. In order to prevent the web from becoming scorched when its movement is halted for any reason, suitable mechanism is provided to remove the plate upon the halting of the moving parts including the rolls 10 and 11. 15

In the present instance, the plate 20 is supported by means of an arm 22 pivotally mounted on a shaft 23 and supported by link-work including a link 24, a bell crank 24a mounted on a shaft 24b and a link 24c. The link 24c is connected to a sleeve 25 which slides on a shaft 26. The shaft is normally rotated by means of gearing (not shown) operated from a belt 27 extending over a roll 28 driven, in the present instance, by means of the conveyor belt 21. The sleeve 25 is carried on a sleeve 28 which is slidably keyed to the shaft 26 and carries one end of a centrifugal toggle mechanism 30, the other end of which is secured to the shaft at 31. Whenever the roll 11, and consequently the shaft 26, is operating the centrifugal toggle mechanism acts to draw the sleeve 28 to the right causing the link-work to swing into the position shown by full lines so as to hold the plate 20 in its operative position. The moment the shaft 26 ceases 30 to rotate, the weight of the plate 20 will act to swing the link-work to the position shown in dotted lines, and to move the plate away from the web. 35

Stripes of wet adhesive are applied transversely 45 to the web by means of an intermittently operated glue roll 33 supplied with a wet adhesive as from a glue trough 34. Desirably the roll 33 is dropped upon the web, lifted momentarily, and dropped again, to provide stripes 35 and 36, and then is moved upwardly to receive glue before the application of two similar stripes. To effect this operation any well known or suitable mechanism including a cam or other means to effect such movement may be utilized. The web is cut 50 into sheets as by means of a rotary cutter 37, which is timed to cut the sheets between each pair of stripes 35 and 36. Each sheet 38 after it is cut is carried by a high speed conveyor 38a over folding rollers 39, under a form which in the present instance consists of a plunger 40 operated in synchronism with the other elements by any well known or suitable mechanism. Stop means 40a is provided to assure proper alignment of the sheet. Wires 40b may be stretched 55 above the sheet to hold it against the conveyor. The plunger serves to press the sheet between the rolls 39 so as to fold the side portions of the sheets upwardly to provide the sides of the bag. The plunger then carries the folded sheet between 60 additional folding members 41 and 42, which move successively against the plunger and fold inwardly first the unglued cut edges of the sheet and then the glued edges; so that the stripes 35 and 36 overlap the other edge portion of the sheet. 65 70 75

The tabs are then turned up and these and the overlapping edge portions sealed, as by a pair of suitably heated rolls 43 and 44 past which the plunger moves the bag. It is to be noted that 5 the upper portion of the plunger is recessed so that the stripes of dried glue 18 and 19 do not contact the plunger. Thus danger of the bag sticking to the plunger or of removing adhesive later needed for the sealing of the bag is avoided. 10 The plunger is desirably recessed about its entire periphery as shown, but may be recessed merely at the sides along which the rolls 43 and 44 move. The plunger projects the bag, as indicated at 45, into a carton 46 on a carton holder 47, and the 15 plunger is thereupon drawn upwardly. Stripper fingers 48 are provided to prevent the withdrawal of the bag with the plunger, and the plunger is preferably formed hollow with an opening to the atmosphere to prevent a differential in air pressure 20 sure being set up. The stripper fingers comprise the ends of a coil spring 48a wound about a shaft 48b.

The lined carton is transferred to a continuous conveyor 49 by suitable mechanism such as a 25 pusher bar 50, and rides directly from this conveyor onto a continuous conveyor 51. It is carried by the conveyor 51 under suitable filling mechanism, such for instance as a weighing machine 52 (Figs. 3 and 4), whereby the bag is 30 filled with suitable ingredients, the unit being held thereunder by a stop-arm 53 which may be arranged to be automatically released by the weighing machine. The filled units reach a stop 53a and are transferred by a pusher rod 54 onto 35 a platform 55 provided with guides 56 and 57, and are moved along the platform by means of arms 58 on an endless continuous conveyor 59 at one side of the platform.

In the present exemplification the units are 40 first carried under a mechanism for spreading the side flap or flaps of the cartons. This mechanism comprises a shaft 60 carrying a wedge-shaped arm 61 which passes between the up-standing side portions of the liner and pushes 45 them and likewise the side flaps outwardly, the shaft 60 being timed so that the arm 61 will move into each unit. While the side flaps are still partially spread, they move under longitudinal bars 62 and 63 which have upturned ends 50 and serve to bring the side flaps to substantially a horizontal position. If a carton having only a single side flap is utilized, only a single bar needs to be provided. In order to bring the forward flap of the carton to a horizontal position, 55 there are provided horizontal arms 64 and 64a which are rotated by vertical shafts 65 and 65a. As these arms move together they not only depress the flap, but also point the forward end of the bag or liner. The flaps of the carton now 60 being out of the way, the top edge portions of the liner may be pressed against each other for sealing. In order that there may be no interstices for the ingress of moisture, the liner is desirably pinched from end to end in a manner 65 which allows for no folds between its ends. Accordingly the portions of the liner carrying the dry adhesive are pressed firmly and effectively into a tightly sealed relationship. When there is a proper adhesive used, such as one having 70 a rubber base,—for instance, rubber latex compositions, rubber solutions, etc.,—this sealing can be readily effectuated by cold rolls, since such adhesives readily bind upon pressure without heat, as indicated in my copending application 75 hereinafter referred to. If a rubber latex com-

position such as set forth in said application is utilized in the coating of waxed paper bags, and dried before sealing, it is desirable that the adhesive be carried on each side of the joint, since when dried the adhesive does not readily unite to a wax surface. To effect this operation, the forward end of the liner is pointed forwardly, as by means such as the arms 64 and 64a, and/or by means such as an arm 66 which is preferably formed of soft rubber and which is carried on properly timed rotating horizontal shaft 67, or by other suitable means. Preferably, as shown, both the horizontal and vertical arms are utilized, altho either may be used independently. In the present instance, as the pointing member 66 slides out of the liner the liner moves between sealing rolls 68 and 69 whereby the side edge portions of the liner are pinched tightly together, so that the dry adhesive carried on its upper edge portions forms a continuous and effectual seal. Because the adhesive is sealed to itself while dry, there need be no apparatus to supply a solvent or other reactivating agent. The front flap and side flaps of the carton pass under the rolls and the rear flap slides under them. 20 25

In order to fold down the top of the liner, there may be provided a plate 70 operated by any suitable cam-controlled or other mechanism which imparts thereto a generally four-way motion,—first in over the bag, then forwardly with the unit, then outwardly and then rearwardly. The particular mechanism exemplified comprises lugs 170 attached to the arms 58 (for the sake of simplicity these are shown only on certain of the exemplified arms) which are arranged to cooperate with pins 171 extending downwardly from the plate 70 to cause the plate, when it is thrust over the bag, to move forwardly with it. The plate is mounted on a reciprocating carriage 172 by means of a bracket 173 which rides on track rods 174 forming a part of the carriage 172. The carriage 172 rides on lateral track rods 175 and is pulled toward stops 176 by means of spring 177. The carriage 173 and plate 70 are urged to the left by means of a spring 178. The carriage is thrust inwardly so as to carry the plate over each unit by means of a rotating cam 179 which is operated from one of the shafts of conveyor 59 by means, including a belt 180, which means causes a proper timing of cam 179. In 30 order to guide the plate 70 forwardly as it is moved inwardly by the cam 179, there is provided a stationary cam member 181, and in order to guide the plate 70 forwardly during its outward movement when released by the cam 179, 35 there is provided a stationary cam member 182. As will be seen, the initial action of the cam 179 is to move the plate 70, guided by the cam 181, quickly over a unit and then to hold it over the unit while the lug 170 presses against the pin 171 and carries the plate forwardly, so as to 40 compress the spring 178. At the end of this forward movement of the plate 70 the cam 179 releases the plate so that the springs 177 draw the carriage and the plate, guided by the cam 182, 45 toward the cam 179 and bring the pin 171 clear of the lug 170. The spring 178 then acts to move the plate rearwardly, whereupon the operation is repeated. By this action, the plate presses the top of the bag flush with the carton and holds it there while the end flaps are folded in over the projecting ends of the bag. The mechanism for performing the latter folding actions comprises a longitudinal bar 71 having an upturned end which folds the forward flap over flush with 50 55 60 65 70 75

the top of the carton proper and an arm 72 carried on a properly timed rotating vertical shaft 73 and acting to fold the rear flap to a forward position where it too moves under the bar 74. 5 In order to seal the carton, glue may be applied to the side flaps as by means of glue rolls 74 and 74a. One side flap may pass from under the bar 62 and be folded over by a bent bar 75, whereupon the other flap may be folded over by 10 a bent bar 76. The carton may then be run between belts 77 and 78 for a sufficient distance to assure that the carton is permanently closed. If a carton having a single side flap is utilized, the closing mechanism may, of course, be suitably 15 modified.

A variety of types of adhesive materials may be utilized as will be readily understood, and if desired different adhesives may be applied by rolls 15—16, and 33 respectively. A particularly 20 desirable type of adhesive for use with waxed paper or the like is disclosed in my co-pending application, Serial No. 649,502, filed December 30, 1932. If this adhesive is so utilized, it is desirable to use both the glue rolls 15 and 16, since, 25 when dry, the adhesive unites more readily with itself than with the waxed paper. When such an adhesive is used it is unnecessary to heat the sealing rolls 68 and 69, but these may be suitably heated electrically or otherwise if the conditions of operation render this desirable. 30

As above indicated, the exemplified method and apparatus may be modified in a variety of ways, a few of which are hereinafter exemplified.

In Fig. 5, there is illustrated a plunger 80 similar to the plunger 40, except that instead of being recessed about its entire periphery at its upper end, it is only recessed at those sides against which the sealing operation is to be performed. The recesses are indicated at 81. There 40 is also exemplified sealing means which comprise heated plates 82, as well as heated rollers 83.

In certain instances, the plunger itself may be heated, one form of heated plunger being exemplified at 84 in Fig. 6. When the plunger is heated, cold rolls 85 may be utilized. It may be noted in this connection that where adhesives, which do not require the use of heat, are utilized, heated members may, of course, be dispensed with. 45

Several of the many types of mechanisms 50 which may be utilized to perform package closing steps in accordance with the invention, are exemplified in Figs. 7, 8, 9 and 10.

In Fig. 7 there is shown a form of apparatus wherein, instead of using a pair of arms, as 64 and 64a, which perform both a flap-bending and liner-pointing function, there is utilized merely a single flap-bending arm 64b. In such a construction the entire pointing action is performed by the pointing arm 66. 55

60 In Figs. 8 and 9, there is shown a modified form of mechanism for bending the portion of the liner which has been sealed between the rolls 68 and 69. This comprises a curved plate 88 which bends the sealed portion of the liners over 65 and presses them downwardly flush with the top of the carton proper. In order to assure a smooth fold line, there is preferably provided a horizontal plate 87, under which the forward flap of the carton may ride. The upstanding portions of the liner are folded over the right hand edge (Fig. 9) of this plate, whereupon the end flaps may be bent over as by members similar to the members 71 and 72, or other suitable members, and the side flaps suitably closed. 70

75 Another form of closing mechanism is illus-

trated in Fig. 10. This comprises a cam plate 88 rotating on a suitably timed shaft 89 provided with an upstanding forward flange 90 and a rearward lug 91. As the package and the plate come together, the flange 90 bears against the upstanding sealed portions of the liner and bends them over the outer edge of the plate completing this action. The lug 91 follows the body of the plate and serves to bend forwardly the rear flap; and the portion of the liner which extends over the forward flap, is bent over by a bar 92 similar to the bar 71, the body of the plate acting to assist in the formation of a fold line in each instance. It is to be noted that the rear flap will still be held bent over in a forward position as 10 it reaches the bar 92. Thereupon the side flap or flaps may be suitably closed. 15

In order to assist in the visualization of the steps hereinbefore described, various stages in the formation of the package are exemplified in 20 Fig. 11. A sheet ready to be formed into a bag is shown at a; at b the sides of the bag are shown bent up; at c the edges of one side are shown bent inwardly; at d the edges of the other side are so shown; at e the tabs are shown folded up 25 and the overlapping portions sealed; at f the bag is shown inserted in a carton; at g the bag is shown pointed ready for sealing; at h it is shown sealed; at i it is shown with the sealed top of the liner bent over; at j the end flaps of the carton are shown closed; at k one side flap is shown closed and at l the completed package is shown. 30

In Figs. 12, 13 and 14, there is shown a mechanism for closing a carton having a side flap equipped with an inserting tab. The side flap, 35 which is held down by a bar such as 63, reaches a bar 93 which passes under the flap proper and under a glue roll 94 which ordinarily is of sufficient width to glue flaps of varying sizes. In order to keep the tab out of contact with the glue 40 roll, there is provided a bar 95, the end 95a of which is curved so as to bend down the flap out of the way of a gluing roll 95 whereby glue is applied to the flap. The bar 95 terminates beyond the roll, and the flap and tab are received 45 in a plate 86 which is curved, so as to bend at the tab inwardly with respect to the flap and then to bend the flap over, so that the tab will be inserted inside the carton at its opposite side, and the side flap laid against the end flaps which 50 have previously been bent inwardly.

As will be readily apparent, packages consisting merely of bags, as well as lined cartons and other types of packages, may be readily formed in accordance with the invention. In Fig. 15 55 there is shown a construction whereby the pointer 66 and sealing rolls 68 and 69 are utilized for sealing an unenclosed bag 97 coming from a filling unit 98 and propelled by conveying means 59a similar to the member 69. 60

Instead of utilizing mechanism such as the conveyor 51, the stop 53a and the transfer arm 54, filled cartons or bags may be moved in a direct line from the conveyor which runs under the filling mechanism onto a conveyor which carries them under the package-closing mechanism. One type of apparatus for this purpose is illustrated in Figs. 16 and 17. In this construction lined cartons or bags carried on the conveyor 51 from the filling mechanism move 65 against removable stops 99 and 100 disposed above the conveyor 101 which serves to carry the package under package-closing mechanism. The conveyor 101 carries spaced lugs 102 which move 70 upwardly and forwardly against the end of a 75

package and push the same forward at a uniform rate. Associated with each lug is a pair of cams 103 and 104 carried at the sides of the conveyor and adapted to bear against the plates 105 and 5 106 attached to the arms 99 and 100, respectively, to spread these arms as each lug rises to engage a package. In order to place the package upon the conveyor 101 so that a lug 102 will rise behind it, there are provided a pair of high-speed driving rolls 107 and 108.

As will be understood, a variety of types of packages may be formed in accordance with the invention in a variety of different ways.

In Figs. 18, 19 and 20, there is exemplified a 15 method and apparatus for forming bags by a different type of shaping operation. Lateral stripes of adhesive may be applied to a web 110 by means of a roll 111 operating similarly to the roll 33, except that a single stripe instead of a 20 double stripe is applied. These stripes are shown at 111a in Fig. 20. The roll 111 extends substantially across the entire width of the web. The web is drawn from a roll 112 under the roll 111 and over a hot plate 113 by means of rolls 114 25 and 115. The hot plate 113 is preferably supported so that it will move away from the web if the motion of the web is stopped for any reason. A mechanism similar to that shown in connection with the plate 20 may be used for this 30 purpose. Adhesive is then applied to one edge of the web by means of a roll 116, similar to the rolls 15, to provide a stripe 116a, and lateral stripes of adhesive just forwardly of the stripes laid down by the roll 111 are applied by an intermittently 35 operable roll 117 similar to the roll 111, except that it is recessed throughout a portion of its length, as indicated at 118, so as to lay down a broken stripe of adhesive 117a (Fig. 20). The web is carried by a conveyor 119 under the rolls 116 40 and 117 and past a cutter member 120 which cuts the web into sheets 121 (Fig. 20). A high-speed conveyor 122 carries each sheet over folding rolls 123 and in the path of movement of a form. In the present instance, this is one of a 45 series of forms 124 carried on an endless conveyor 125. The sheet 121 moves over the rolls 123 with the stripe of dry adhesive 111a at the forward edge of the sheet, and each form is recessed as indicated at 126 so that the form will 50 not contact the stripe. Each form carries a stop plate 128 at its inner end. As each form moves between the rolls 123, the ends of the sheet are folded upwardly about the form, and as the form moves downwardly these ends are held in folded 55 position by plates 127, 128, 129 and 130. In order to bend down the unglued upper end of the sheet, there is provided a reciprocating roll 131 carried 60 on arms 132 from a suitably operated shaft 133. The roll 131 moves inwardly between the plates 128 and 130 and moves the unglued upper end of the sheet against the top of the form and then moves rapidly away from the form. Slightly below the roll 131 (Fig. 19) there is provided a 65 similarly operated roll 134 carried on arms 135 from a shaft 136 having a similar reciprocal action imparted thereto. The roll 134 acts to fold over the glued upper end of the sheet into overlapping relationship with the unglued upper end of the sheet, and to seal it thereagainst. Desirably 70 in most instances, the roll 134 will be a heated roll. It is to be noted that the forms 124 are of such size that when the sheet is against the stop plate 128, the edge thereof carrying the broken stripe of adhesive 111a projects beyond the outer end of the form. In order to fold this edge in-

wardly and to seal the bottom of the bag, there are provided side folding plates 137 and 138 adapted to act successively to fold in the unglued portion of the edge and to fold a portion of the edge which carries adhesive stripe 111a into overlapping relationship therewith. The plates 137 and 138 are carried, respectively, on shafts 139 and 140 to which a properly timed reciprocal action is imparted by any well known or suitable mechanism. The upstanding tabs on the bottom 10 of the bag are thereupon closed. To effect this action there is provided a plate 144 having an upturned end 141 for bending over the forward tab and an arm 142 carried on a rotating shaft 143 for bending forward the rearward tab at a 15 time such that it also will move under the plate 144. Desirably there is provided a heated plate 145 which may be part of, or independent of, the plate 144 for the purpose of sealing the tabs and the overlapping portions at the bottom of the 20 bag. The bag so formed may be removed and inserted into a carton manually or by suitable mechanism, or a carton may be formed around the bag on the form 124 as it continues in its course in a manner well known in the art, and the lined 25 carton suitably removed. The bags or lined cartons thus formed may be filled and sealed in any of the exemplified manners or otherwise, as desired.

It may be noted in this connection that the 30 expression "top of the bag" as used herein indicates the end of the bag which is open after the bag is formed, regardless of the position of the bag at any particular stage in the operation.

In Fig. 20 *m* illustrates the sheet 121 ready for 35 folding. The sheet is shown after the action of the rolls 123 at *n*, of the roll 131 at *o*, of the roll 134 at *p*, of the plate 137 at *q*, of the plate 138 at *r*, and of the plate 144 at *s*. The finished bag, after the final action of the arm 142, the plate 144 40 and the plate 145, is shown at *t*.

Since certain changes in carrying out the above 45 method and in the constructions set forth, which embody the invention may be made without departing from its scope, it is intended that all matter contained in the above description or shown in the accompanying drawings shall be interpreted as illustrative and not in a limiting sense.

Having described my invention, what I claim 50 as new and desire to secure by Letters Patent, is:

1. The method of forming packages, which comprises providing a stripe of dry adhesive on one edge of a sheet, adhesive being provided elsewhere on the sheet for use in the formation of a bag from the sheet, forming the sheet into a bag with said stripe of dry adhesive on the inside of the top of the bag, filling the bag, and sealing the top by means of said stripe of dry adhesive without said stripe being reactivated. 55

2. The method of forming packages, which comprises providing a stripe of dry adhesive on one edge of a sheet, adhesive being provided elsewhere on the sheet for use in the formation of a bag from the sheet, forming the sheet into a 60 bag with said stripe of dry adhesive on the inside of the top of the bag, said forming operation being conducted without contacting said stripe, filling the bag, and sealing the top by means of 65 said stripe of dry adhesive without said stripe being reactivated. 70

3. The method of forming packages, which comprises providing a stripe of adhesive on one surface adjacent one edge of a sheet, adhesive being provided elsewhere on the sheet for use in 75

the formation of a bag from the sheet, forming the sheet into a bag with said stripe of adhesive on the inside of the top of the bag, said forming operation being conducted without contacting said stripe, filling the bag, and sealing the top by means of said stripe of adhesive and without contacting said stripe with the opposite face of said sheet.

4. The method of forming packages, which 10 comprises providing a stripe of dry adhesive on at least one side of a web, applying adhesive on said web in transverse stripes, transversely cutting the web along lines with adhesive on either side thereof, forming bags by converting each 15 cut sheet into bag shape with the side edges of the web at the top of the bag, sealing the edges adjacent the cuts, filling the bags, and sealing the top of each bag by means of initially provided adhesive.

5. The method of forming packages, which 20 comprises applying a stripe of adhesive on each side of a web, drying the adhesive, applying adhesive on said web in transverse stripes, transversely cutting the web along lines with adhesive 25 on either side thereof, forming bags by converting each cut sheet into bag shape with the stripes of dry adhesive at the top of the bag and sealing the edges adjacent the cuts, filling the bags, and sealing the top of each bag by pressing together 30 said stripes of dried adhesive.

6. The method of forming packages which 35 comprises applying stripes of adhesive laterally on a web, drying the adhesive, applying adhesive elsewhere on the web between spaced stripes, cutting the web to provide sheets each having a stripe of dry adhesive adjacent one edge, forming each sheet into a bag with said stripe of dry adhesive adjacent its top, filling the bag, and sealing the top by means of the dry adhesive adjacent its 40 top without said stripe being reactivated.

7. The method of forming packages, which 45 comprises providing dry adhesive along certain of the edges of a sheet, forming the sheet into bag shape with said dry adhesive on the inside of its top, filling the bag, pointing one end of the bag, and sealing the bag progressively from said 50 end to the other end by means of said dry adhesive.

8. The method of forming a package, which 55 comprises providing stripes of adhesive adjacent certain of the edges of a sheet of moisture-proof material, forming the sheet into bag shape by an operation involving the sealing of overlapping edges by means of certain of said stripes, others of said stripes being disposed at the inner edge 60 portions forming the top of the bag at least along one side and along the adjacent halves of the ends of the bag, filling said bag and sealing the bag by a flat seal wherein the ends are pointed and the seal extends without creases from one end to the other end of the bag.

9. The method of sealing lined cartons which 65 comprises moving lined cartons along a path, laterally spreading the side flap or flaps of the carton, bending the forward flap forwardly, pointing the forward end of the liner, pinching the liner from its forward end rearwardly to seal the same, bending the pinched portion to one side, bending the forward flap of the carton rearwardly and the rear flap of the carton forwardly, and sealing the side flaps of the carton.

10. The method of sealing lined cartons which 70 comprises moving lined cartons along a path, laterally spreading the side flap or flaps of the carton, bending the forward flap forwardly, point-

ing the forward end of the liner, pinching the liner from its forward end rearwardly to seal the same, bending the pinched portion to one side and, while it is held in bent position, bending the forward flap of the carton rearwardly and the rear flap of the carton forwardly, and sealing the side flaps of the carton.

11. Package sealing apparatus comprising means to press the top edge portions of a bag together progressively to seal the same, means 10 to cause relative movement of a bag and said sealing means, and means to point the end of the bag toward said sealing means as it enters the same.

12. Package sealing apparatus comprising 15 means including a roller for pinching the top of a bag, means to hold an unsealed bag, means to cause relative movement of the aforesaid means to cause a bag to be operated on by the pinching means, and means to point the end of the 20 bag toward the pinching means before the pinching means becomes operative.

13. Package sealing apparatus comprising 25 means including a roller for pinching the top of a bag, means to hold an unsealed carton containing an unsealed bag, means to cause relative movement of the aforesaid means to cause a bag to be operated on by the pinching means, means to move the forward flap of a carton out of the 30 path of the pinching means before the movement brings the pinching means thereabove, and means to point the end of the bag toward the pinching means before the pinching means becomes operative.

14. Package forming apparatus including 35 means for moving an open carton containing an open liner along a path, means to spread the side flap or flaps of the carton, means arranged to move inwardly and forwardly on opposite sides of the path for pointing the forward end of the 40 liner and for moving the forward flap of the carton forwardly, and means to progressively pinch the liner from its pointed end rearwardly to seal the same.

15. Package forming apparatus including 45 means for moving an open carton containing an open liner along a path, means to spread the side flap or flaps of the carton, means arranged to move inwardly and forwardly on opposite sides of the path for pointing the forward end 50 of the liner and for moving the forward flap of the carton forwardly, and means arranged to move forwardly and upwardly to accentuate the pointing of the liner.

16. Package forming apparatus, comprising 55 means for moving an open carton containing an open liner along a path, means to spread the flaps of the carton, means to point the forward end of the liner forwardly, means including a pinching roll for receiving the pointed end of the 60 liner and for closing the liner, means to fold over the closed portion of the liner, means to fold the end flaps inwardly and means to close the carton.

17. Package forming apparatus, comprising 65 means for moving an open carton containing an open liner along a path, means to spread the flaps of the carton, means including a finger formed of yieldable material and rotating on a horizontal axis to point the forward end of the 70 liner forwardly, means including a pinching roll for receiving the pointed end of the liner and for closing the liner, means to fold over the closed portion of the liner, means to fold the end flaps inwardly, and means to close the carton.

18. Package forming apparatus, comprising means for moving an open carton containing an open liner along a path, means to spread the flaps of the carton, means to point the forward 5 end of the liner forwardly, means including a pinching roll for receiving the pointed end of the liner and for closing the liner, a transversely-moving plate adapted to move the closed portion of the liner laterally, a stationary plate in the 10 path of movement of the projecting portions of the unit being moved, means to move rearwardly-projecting portions of the unit forwardly, and means to close the carton.

19. Package forming apparatus, comprising 15 means for moving an open end carton containing an open liner along a path, means to spread the flaps of the carton, means to point the forward end of the liner forwardly, means including a pinching roll for receiving the pointed end 20 of the liner and for closing the liner, a curved plate in the path of movement of the pinched portion of the liner for bending the same downwardly, a stationary plate in the path of movement of the projecting portions of the unit being 25 moved, means to move rearwardly-projecting portions of the unit forwardly, and means to close the carton.

20. Package forming apparatus, comprising 30 means for moving an open carton containing an open liner along a path, means to spread the side flap or flaps of the carton, longitudinal bar means in the path of movement of the carton to further spread the side flap or flaps, means to

move the forward flap forwardly, means to point the forward edge of the liner, pinching-roll means adapted to receive the forward flap therebeneath and to receive the pointed end of the liner and to pinch the liner, means to move the 5 pinched portion of the liner laterally, means to fold the end flaps inwardly, and means to fold and secure the side flap or flaps.

21. The method of forming packages which comprises providing dry adhesive along certain 10 edges of a sheet, forming the sheet into bag shape with said dry adhesive on the inside of its top, filling the bag, and sealing the bag by means only of said dry adhesive while said adhesive is dry. 15.

22. The method of forming packages which comprises providing dry adhesive along at least a part of the periphery of a sheet, forming the sheet into bag shape with said dry adhesive on the inside of its top, filling the bag, and sealing 20 the bag by means only of said dry adhesive while said adhesive is dry.

23. The method of forming packages which comprises providing a stripe of dry adhesive on one edge of a sheet, providing wet adhesive elsewhere on the sheet, forming said sheet into an open bag by means of said wet adhesive and with said stripe of dry adhesive on the inside of, and along, the top of the bag, whereby said stripe 25 is in a position for finally sealing the top of said bag without the reactivating of said stripe. 30

ADRIAN O. DALLER.
